UNITED STATES PATENT OFFICE.

ANDREW HOWARD, OF WILKINSBURG, PENNSYLVANIA.

DESIGN FOR A CHIMNEY.

SPECIFICATION forming part of Design No. 29,837, dated December 20, 1898.

Application filed November 25, 1898. Serial No. 697,461. Term of patent 7 years.

To all whom it may concern:

Be it known that I, ANDREW HOWARD, a citizen of the United States, residing at Wilkinsburg, in the county of Allegheny and State of Pennsylvania, have invented a certain new and useful Design for Chimneys for Incandescent Gas-Lights; and I do hereby declare the following to be a full, clear, and exact description of the invention, such as will enable others skilled in the art to which it appertains to make and use the same.

My design has relation to glass chimneys.

The accompanying drawing is a side view of a glass chimney showing my new design.

The chimney consists of the cylindrical body part A, surmounted by the smaller cy-

lindrical part E, between which and the body part A are the rounded shoulders B B', of different diameters. The base of the body part A is rounded to correspond with the shoulder B, and below this is a narrowed cylindrical extension or neck F.

Having thus described my invention, what I claim as new is—

The design for a chimney herein shown and described.

In testimony whereof I affix my signature in presence of two witnesses.

ANDREW HOWARD.
